DESIGN FOR A MAGAZINE RACK

William Gerald Gray, Harrisonville, Mo.

Application January 16, 1943, Serial No. 109,275

Term of patent 14 years

To all whom it may concern:

Be it known that I, William Gerald Gray, a citizen of the United States, residing at Harrisonville, in the county of Cass and State of Missouri, have invented a new, original, and ornamental Design for a Magazine Rack, of which the following is a specification, reference being had to the accompanying drawing, forming part thereof.

Fig. 1 is a perspective view of a magazine rack, showing my new design;

Fig. 2 is a side elevational view; and

Fig. 3 is a top plan view thereof.

I claim:

The ornamental design for a magazine rack, as shown.

WILLIAM GERALD GRAY.
